UNITED STATES PATENT OFFICE.

GABRIEL E. ROHMER, OF BROOKLYN, NEW YORK.

SHOE-HEEL.

1,356,829.

Specification of Letters Patent. Patented Oct. 26, 1920.

Application filed February 20, 1919. Serial No. 278,230.

To all whom it may concern:

Be it known that I, GABRIEL E. ROHMER, a citizen of the United States, and resident of the borough of Brooklyn, in the county 5 of Kings and State of New York, have invented certain new and useful Improvements in Shoe-Heels, of which the following is a specification.

The present invention relates to shoe 10 heels, and while the present disclosed embodiment shows particularly a shoe heel for ladies' shoes, it will be apparent from the description hereinafter given that the invention is not restricted to this use, but may 15 be used upon heels for men's shoes, or in fact in any connection in which the principle will be applicable.

An object of the invention is to provide 20 cushioning means within the heel adapted to take up the shock of impact in walking and to compensate the rigidity of the heel in walking or standing, such cushioning means being subject only to transmitted 25 forces in absorbing and compensating shocks, as distinguished from those heels having exposed cushioning means, which directly engage the ground in walking. A further object is to provide a heel which may be attached and detached with facility, 30 will be securely held to the shoe and will be wear resisting to a high degree.

The invention is particularly adapted to 35 aluminum, bakelite, or other rigid shoe heels made of moldable material, which in the absence of cushioning means are inflexible, rigid and extremely tiresome upon the wearer, imparting shocks from the impact of walking directly to the wearer's heel. I propose to provide an inner cushioning 40 means, having a relatively large area as compared to the small surface which contacts with the ground, so that the shocks upon the heel will be distributed over and absorbed by a relatively large surface, and 45 will, therefore, be felt to a very small degree by the wearer. I further propose to provide in connection with the main cushioning means auxiliary air cushion means to the end that the heel will be yieldably 50 supported either during walking or when there is merely a dead weight thereon, as when standing still, thereby greatly adding to the comfort of the wearer. A still further object is to provide a heel which will 55 be yieldable so that it will not break loose

from the shoe when any great weight or distortion is placed thereon.

I further propose to provide in a heel having interior cushioning means, an improved contact cushion means, that is, an 60 exposed cushion to contact with the ground, and adapted to coöperate with the interior cushioning means to provide a highly resili- 65 ent heel, which will make contact with the ground substantially noiseless, will relieve 70 the rigid portion of the heel of strains, and will add materially to the comfort of the wearer. Other objects are to provide such a contact cushion which may be attached and removed with facility, will not become 75 displaced during use, will have in connection therewith an air cushion, and as one embodiment I propose to provide a contact cushion which may be readily attached and detached without the use of screws, nails, 80 or the like, and which while in use will be securely held against displacement and distortion.

With the above and other objects in view, 85 embodiments of my invention are shown in the accompanying drawings, and these embodiments will be hereinafter more fully described with reference thereto, and the invention will be finally pointed out in the claims.

In the accompanying drawings:

Fig. 1 is a plan view of a lady's shoe heel embodying one form of my invention;

Fig. 2 is a vertical sectional view thereof, taken along the line 2-2 of Fig. 1; 90

Fig. 3 is a vertical sectional view of a modified form of construction;

Fig. 4 is a perspective view of a contact cushion formed according to my invention;

Fig. 5 is a fragmentary sectional view 95 of the lower portion of a heel provided with a modified form of contact cushion, formed according to my invention and in which the same is attachable and detachable without the use of screws, nails or the like; and 100

Fig. 6 is a plan view of the contact cushion shown in Fig. 5.

Similar reference characters indicate corresponding parts throughout the several figures of the drawings.

Referring to the drawings, and more particularly Figs. 1 and 2 thereof, the heel 10 is in the present embodiment of cast metal (die-cast aluminum), molded bakelite, or other suitable material, and it will be under- 110

stood that other types of heels may be employed. In its upper enlarged end there is provided a recess 11, the sides of which are inclined to the bottom, the lateral configuration of the recess substantially following the contour of the heel. A well or socket 12 is provided in the base of the recess, which makes the heel substantially lighter, and, as it will presently appear, 10 forms an air pocket.

Within the recess 11 there is provided a resilient block 13, preferably of rubber, its periphery being beveled as at 13^a to engage the inclined sides of the recess with a wedging fit, the lower surface of the block being raised from the base of the recess to form therebetween an air cushion space, the socket 12 constituting a portion of this air cushion space. The upper surface of the resilient block is substantially flush with the upper surface of the heel.

The heel is secured to the resilient block by means of screws 14 and 15 passing through holes 16 and 17 in the block, and engaging threaded openings 18 and 19 in the base of the recess 11, disposed forwardly and rearwardly of the pocket 12, the screw heads being countersunk in depressions 20 and 21, which permit of considerable deflection of 30 the block as indicated by the dotted lines 50 (Fig. 2) without projection of the screw heads.

The reduced end of the heel is recessed as at 22, and a piece of leather 23 is set therein 35 and secured by means of a screw 24, and an exposed cap of leather 25 is secured thereto over the end of the heel by means of nails 25^a passing up into the piece 23, the points of the nails being upset against the metal 40 base of the recess 22.

A bead 26 is formed at the lower end of the heel, and above this bead the heel is covered with a coating of enamel, or a covering of cloth or leather 27, the bead being exposed 45 so that it has the appearance of the separate metallic plates usually provided between the end of the heel and the leather cap, while at the same time it has the function of forming an abutment for the covering. Covering 27 overlaps the upper edge 50 of the heel in the usual manner as at 27^a.

The heel is attached to the shoe by means of diagonally driven nails 28 driven through the resilient block 13, the upper 28^a of the 55 shoe being inserted and glued between the inclined surface of the recess and the beveled periphery of the block, the points of the nails being upset against the metal surface of the heel. The heel being entirely attached by means of the screws 14 and 15, it may be 60 very readily attached and detached by insertion and removal of the screws.

The sole of the shoe is attached by nails 29, which are preferably arranged alternately to nails 28, and which are driven in 65

the same manner through the resilient block 13 and the upper 28^a of the shoe against the metal surface of the heel, but of greater length. I have indicated in dotted lines in Fig. 2 the manner of attaching the sole.

In walking, the shocks of impact are taken up by the resilient block and the air cushion beneath the same, the shocks being distributed from the small point of contact with the ground over a substantially large 75 area of the cushioning means, their intensity being so reduced and distributed by the cushioning means that they are practically unfelt by the wearer. While standing, the weight of the wearer is not rigidly supported as with the old form of heels, but instead rests upon resilient cushioning means which in connection with the air cushion functions to a considerable degree when a mere weight is placed thereon without any shock of impact. The flexibility of the heel permits of 80 much easier walking without the danger of breaking off the heel, relieving the shoe of the uncompensated strains which are set up in the rigid forms of shoe heels at present in 85 use, so that a shoe provided with a heel according to the present invention will be longer lived, more comfortable and will retain its shape and appearance for a greater time than has heretofore been possible.

In Fig. 3 I have illustrated a modified form of my invention in which a laminated steel spring 30 is secured to the upper surface of the resilient block 13 and extends along the arch of the shoe. This spring is 100 secured in place by the screws 14 and 15 which secure the heel to the block 13, apertured bosses 31 and 32 being struck up from the spring and which engage the surface of the depressions 20 and 21 of the block 13, the 105 ends of the bosses being turned inwardly as at 31^a and 32^a to engage beneath the screw heads.

Upon the under surface of the block 13 there is provided a projecting portion 33, 110 which fits into the socket 12, forming a greater cushioning area, and at the same time resiliently supporting the upper portion of the block 13 centrally and substantially within the lines of force directed from 115 the contacting edge of the heel. The wall of the socket 12 is spaced away from the surface of the portion 33, as at 34, to permit of the expansion of the cushion.

At the base of the heel there is provided a 120 socket 35 relatively deep and of oval or other non-circular cross section. A heel cap 36 formed of rubber or other suitable resilient material and shaped to conform to the lateral contour of the heel and provided at 125 its upper side with a plug or projection 37 of oval or non-circular contour corresponding to the socket 35, is adapted to fit snugly into the socket, the same being flattened at its upper side so as to form an air pocket 130

38 above the same and within the pocket. The cap is secured to the heel by means of a screw 39 passing upwardly through the same and into the metal of the heel, the head 40 of the screw being countersunk in an enlargement 41 of the hole 42 provided through the cap. The corner 43 between the base of the heel and the socket is rounded so that it does not cut into the cap. The tapering 10 of the projection 37 and the socket 35 results in a wedging fit of the block, the shock absorbing action being substantially similar to that of the upper cushioning means, the air cushion above the cap giving increased 15 resiliency and permitting of considerable deflection when weight is exerted thereon without the shock of impact. In walking or standing the two cushions have a compensating action, the upper cushion receiving the 20 shocks from the heel of the wearer while the lower cushion receives the impact shocks in walking and each helps to a considerable extent the functioning of the other.

In Figs. 5 and 6 I have illustrated a 25 further modified form of heel cap according to my invention and which is attachable and detachable without the use of screws, nails or the like. The lower end of the heel is provided with a socket 44 having a reduced 30 neck 45 formed by a pair of opposed projecting shoulders 46 and 47 having lateral upper faces and rounded lower faces flared to the periphery of the heel. The heel cap is formed of rubber or other suitable resili- 35 ent material and consists of a lower exposed portion 48 conforming at its periphery to the contour of the heel, and provided at its upper side with a plug or projection 49 of oval or other non-circular shape and flat- 40 tened at its upper side as at 51. The plug is cut out as at 52 and 53 at its opposed longitudinal sides. The cap is attached by forcing the plug into the socket under compression, the enlarged portion engaging 45 above the shoulders 46 and 47 to lock the same in place. The plug is rounded as at 54 and this rounded portion cooperates with the rounded under side of the shoulders 46 and 47 to facilitate attaching of the heel. 50 The periphery of the plug as also the socket is tapered so that the plug engages the socket with a wedging fit and an air cushion space 55 is provided above the plug. A canalization 59 is provided in the plug extending downward from the air cushion space 55, and constitutes an additional air cushion space. The space 56 between the ends of the heel and the cap prevents distortion or warping of the cap and main- 55 tains at all times a snug fit between the cap and the peripheral portions of the heel, at the same time providing a space for deflection of the cushion. In order to eliminate 60 vacuum in the air cushion space a restricted air duct 57 is provided in the heel extending 65

to the socket, and if desired an air duct may be provided in the cap itself.

In Fig. 6, which is a plan view of the heel cap the canalization 59 is omitted, and I intend this form, without the canalization as 70 a further embodiment of my invention.

In the forms of my invention shown in Figs. 1 to 4, it will be noted, air is admitted and may escape slowly and under pressure from the air pockets between the surface of the screws and the screw holes, or if desired, other air ducts may be provided so as to eliminate vacuum. It will be understood that the heel caps shown in Figs. 3 and 4 may also be embodied in the form of 80 my invention shown in Figs. 1 and 2, and that the heel cap shown in Figs. 5 and 6 may be embodied in the forms shown in Figs. 1 to 4.

I have illustrated and described preferred 85 and satisfactory embodiments of my invention, but it is obvious that changes may be made therein within the spirit and scope thereof, as defined in the appended claims.

I claim:

1. In combination with a shoe, a shoe heel comprising a main relatively hard main heel portion provided at its shoe engaging side with a recess, cushioning means disposed within said recess, the upper of said 90 shoe extending between said main heel portion and said cushioning means, and nails passing through said cushioning means, and said upper and upset against the material of said main heel portion to secure said upper 100 to said heel.

2. In combination with a shoe, a shoe heel comprising a main heel portion provided at its shoe engaging side with a recess, cushioning means disposed within said recess, the upper of said shoe extending between said metal of said main heel portion and said cushioning means, nails passing through said cushioning means and said upper and upset against said main heel portion to secure said upper to said heel, and removable means attaching said main heel portion to said cushioning means. 105 110

3. In a shoe heel, a main heel portion provided at its upper part with a recess, a resilient cushioning block disposed in said recess and extending over substantially the greater portion of the upper surface of said heel, said recess having its sides inclined inwardly to its base, said cushion having its 115 sides correspondingly inclined but of less thickness than the depth of said recess, said cushion having its upper surface substantially flush with the upper surface of said main heel portion, and its lower surface 120 spaced from the base of said recess to form an air pocket. 125

4. In a shoe heel, a main heel portion provided at its upper part with a recess, a resilient cushioning block disposed in said 130

- recess and extending over substantially the greater portion of the upper surface of said heel, said recess having its sides inclined inwardly to its base, said cushion having its 5 sides correspondingly inclined but of less thickness than the depth of said recess, said cushion having its upper surface substantially flush with the upper surface of said main heel portion, and its lower surface 10 spaced from the base of said recess to form an air pocket, a pair of attaching screws extending through said cushioning block and screwed into said main heel portion, the heads of said screws being countersunk in 15 said cushioning block to permit deflection of said cushioning block without projection from the upper surface of said screw heads.
5. In a shoe heel, a main heel portion provided at its upper part with a recess, said 20 recess being provided substantially centrally with a downwardly extending pocket, a resilient cushioning block disposed in said recess and extending over substantially the greater portion of the upper surface of said 25 heel, said recess having its sides inclined inwardly to its base, said cushion having its

sides correspondingly inclined but of less thickness than the depth of said recess upon said cushion, having its upper surface flush with the upper surface of said main heel 30 portion, and its lower surface spaced from the base of said recess to form an air pocket, and an extension disposed centrally of said cushioning block, and engaging said pocket.

6. In a shoe heel, a main heel portion provided at its upper part with a recess, a resilient cushioning block disposed in said recess and extending over substantially the greater portion of the upper surface of said heel, said recess having its sides inclined inwardly of its base, a pair of attaching screws extending through said cushioning block and screwed into said main heel portion, the heads of said screws being countersunk in 40 said cushioning block, and an arch spring 45 extending over the upper surface of said heel and provided with portions engaged beneath the heads of said screws, said portions permitting deflection of said cushioning block without projection of said screw heads. 50

GABRIEL E. ROHMER.
